UNITED STATES PATENT OFFICE.

DIMITRI SENSAUD DE LAVAUD, OF SÃO PAULO, BRAZIL.

MACHINE FOR THE MANUFACTURE OF PIPES, CYLINDERS, &c.

1,223,676.

Specification of Letters Patent. Patented Apr. 24, 1917.

Application filed July 21, 1916. Serial No. 110,485.

To all whom it may concern:

Be it known that I, DIMITRI SENSAUD DE LAVAUD, a citizen of Brazil, residing at São Paulo, State of São Paulo, Brazil, have 5 invented new and useful Improvements in Machines for the Manufacture of Pipes, Cylinders, &c., of which the following is a specification.

My invention relates to machines for casting pipe and similar hollow bodies.

An object of my invention is to provide a machine in which the pipe is cast under centrifugal force, and at the same time is subjected to the action of a roller, which 15 exerts a pressure upon the metal as it hardens, and serves to determine the thickness of the pipe. Another object of my invention is to provide a machine in which the pipe as formed is moved out from the mold, 20 so that the length of the pipe is determined, not by the size of the mold, but by the quantity of metal poured in. A further object of the invention is to provide efficient means for cooling the mold and the 25 roller cylinder.

My invention consists in the construction, combination and arrangement of parts as herein illustrated, described and claimed.

In the accompanying drawings forming 30 part hereof, I have illustrated a form of embodiment of my invention, in which drawings similar reference characters designate corresponding parts, and in which:

Figure 1 is a vertical longitudinal section 35 taken approximately through the center of the mold;

Fig. 2 is a vertical transverse section taken approximately on the line 2—2 of Fig. 1, looking in the direction of the arrow;

Fig. 3 is an elevation of the machine 40 viewed from the right hand end, as shown in Fig. 1.

Fig. 4 is a detail of a machine having a plurality of rolling cylinders.

Referring to the drawings, a shell 1 of cast iron or other suitable material is provided, which carries the mold 2. The mold 2 is rotatably mounted upon ball-bearings 12, and is provided with a gear wheel 11 or other 50 suitable means by which it is rotated. At one end of the mold is provided a pouring trough 3. At the same end of the mold 2 is disposed a changeable inwardly projecting ring or flange 2^a which serves to prevent 55 the molten metal from leaving the mold at

this end, and also to determine the thickness of metal in the pipe.

A roller 4 is disposed in bearings 10, so as to have one end project within the mold 2. This roller is provided with a gear wheel 80 8, or other suitable driving means; and has disposed upon its outer surface where it extends within the mold 2, a helical depression 8 or raised portion 9. The shortest distance between the roller 9 and the interior of the 65 mold 2, at the bottom as shown in the drawings, determines the thickness of the metal in the pipe.

In order to provide for the cooling of the mold, space is provided between the mold 2 70 and the shell 1, to which water is admitted through the passage 15, the water being discharged from the passage 16. The roller 4 is provided with a pipe 5 centrally located within the roller, and extending the length 75 thereof, having at the end of the roller, adjacent the mold, openings 5^b connecting the interior of the pipe 5 with the space between the pipe 5 and the inner surface of the roller 4. A pipe 6 projects into the open 80 end of the pipe 5 for the purpose of supplying water thereto, and at this same end of the roller, there is a partition supporting the pipe 5, having holes 5^c cut therein to allow the water to escape from the space between the pipe 5 and the inner surface of the roller 4. A casing 7 is provided to receive 85 the water discharged from the roller 4.

The pipe being formed is designated by 90 the numeral 17. As this emerges from the mold, it is received by the guiding rollers 14, which are provided with helically cut surfaces similar to the surface of the rolling cylinder 4. Two of these rollers 14 are 95 rotatably mounted in the base 13, and the upper roller 14 is carried on an arm 20 pivotally mounted on the base 13, and is caused to bear against the pipe by the counter weight 19.

In the operation of the machine, the mold 100 2 and the roller 4 are driven through their respective gears 11 and 8 in the same direction of rotation. A quantity of metal sufficient to make the length of pipe desired is poured into the funnel 3, and as it enters 105 the mold it is thrown out by centrifugal force against the inner surface of the mold, and is simultaneously acted upon by the roller 4, which serves to smooth out the inner 110 surfaces of the pipe, and to determine the

- exact thickness of the metal forming the pipe. The water flowing through the space between the shell 1 and the mold 2, and through the interior of the roller 4, serves 5 to keep the roller and the mold cool, and causes the pipe as it comes in contact with the mold to immediately solidify. The helix 9 upon the roller 4 acts upon the pipe as it is formed, moving the same to the right, as 10 shown in Fig. 1; the finished pipe is thus ejected. As the pipe comes from the mold it is received upon the lower rollers 14, and the upper roller 14 is then placed over the pipe, and is caused to exert pressure upon 15 the pipe by the counter weight 19. The pipe rotating in frictional contact with the rollers 14 causes them to rotate, and the helical surfaces of these rollers act upon the pipe and assist in withdrawing it from the mold. 20 As indicated by the detail, Fig. 4, in place of the single roller 4, a plurality of rollers 4^a may be used.

Having now described my invention, I claim as new and desire to secure by Letters 25 Patent:

1. In a casting machine, the combination comprising a rotary mold, and a roller disposed within said mold.
2. In a machine for casting hollow bodies, 30 the combination comprising a rotary mold, a roller disposed within said mold, and means for continuously ejecting a casting as formed.
3. In a casting machine, the combination 35 comprising a rotary mold, a roller disposed within said mold, and ejecting means formed on the outer surface of said roller.
4. In a casting machine, the combination comprising a rotary mold, and a roller dis- 40 posed within said mold, said roller having a helical channel cut in its outer surface.
5. In a casting machine, the combination

comprising a rotary mold, a roller disposed within said mold, and means for cooling said mold and roller. 45

6. In a casting machine, the combination comprising a rotary mold, a roller disposed within said mold, means for ejecting the casting, and receiving rollers. 50

7. In a casting machine, the combination 55 comprising a rotary mold, a roller disposed within said mold, means for ejecting a casting, and receiving rollers having formed thereon means for withdrawing the casting.

8. In a pipe casting machine, means for 55 withdrawing the pipe comprising means for rotating the pipe, rollers in frictional contact with the pipe, and helically arranged gripping means on said rollers, whereby axial movement is imparted to the pipe. 60

9. In a pipe casting machine, means for withdrawing the pipe comprising rollers in frictional contact with the pipe, said rollers having helically arranged gripping means 65 on their surfaces, and means to rotate said rollers.

10. In a casting machine, the combination comprising a rotary mold having inlet and discharge ends, a coacting roller disposed within said mold, means for pouring the 70 molten metal into the inlet end of said mold, and a removable ring disposed at said inlet end of the mold and projecting radially inward from the inner surface of the mold.

11. In a casting machine, the combination 75 comprising a shell, a mold rotatably carried within said shell, the space between said mold and shell forming a water jacket, and a roller disposed to rotate within said mold, said roller having interior channels for the 80 circulation of cooling water.

In testimony whereof I have signed my name to this specification.

DIMITRI SENSAUD DE LAVAUD.
